ABSTRACT OF THE DISCLOSURE

Pipe-cleaning brush with a cylindrically tubular body of rubber or the like, internally clad with a flexible fabric liner and externally provided with a pair of annular grooves adjacent its ends, the surface of the body between these grooves being formed with numerous pits to receive tufts of bristles; the body is seated, at least by its ends, on a rigid cylindrical support, which may be rotatably mounted on a central rod, and is under axial pressure from a pair of relatively displaceable end members whereby the array of bristles bulges outwardly with the tubular body assuming a barrel-shaped configuration.

My present invention relates to a brush for the cleaning of pipes and other ducts such as, for example, the tubes of a boiler.

The general object of my invention is to provide a brush for the purpose described whose bristles, carried on an elastic cylindrical body, will readily adapt themselves to internal ridges, threads or other projections of a pipe to be cleaned, yielding inwardly when necessary and expanding again outwardly after the obstruction has been cleared.

A more particular object of this invention is to provide means in such brush for conveniently adjusting the shape and, with it, the degree of flexibility of the bristle-carrying body whenever such resetting is required because of the fatiguing of the elastomeric material.

These objects are realized, pursuant to the present invention, by the provision of a pipe-cleaning brush whose bristle-carrying cylindrical body is of a tubular construction and rests, at least by its ends, on a rigid cylindrical support between a pair of end members whose axial separation is adjustable for the exertion of axial pressure upon the tubular body whereby the latter bulges outwardly to assume a generally barrel-shaped configuration. This configuration is, of course, also shared by the surrounding set of bristles which advantageously form tufts set in a multiplicity of pits on the outer surface of the body. To facilitate its outward bulging, I prefer to provide the outer surface of the body with a pair of annular peripheral grooves at the support ends; a flexible but substantially inelastic inner liner, such as a fabric sheet, is advantageously bonded to or imbedded in the surface of the body to strengthen it against excessive deformation.

The tubular bristle carrier of my improved brush may be made in a single piece, without any seams or joints, and can thus be manufactured not only from natural rubber but also from a variety of synthetic elastomers which are not readily susceptible to heat sealing.

According to another advantageous feature of my invention, the rigid support for the tubular elastomeric body is rotatably journaled on an extension of a brush handle so that the array of bristles may turn freely, e.g. when following a helicoidal channel on the inner wall of a pipe to be cleaned.

The invention will be described in greater detail with reference to the accompanying drawing in which:

FIG. 1 is an axial sectional view of a pipe brush embodying my invention;

2

FIG. 2 is an elevational view, partly in axial sections, of a second embodiment;

FIG. 3 is a view similar to FIG. 2, showing a modification of the previous embodiment; and

FIG. 4 is a view similar to FIG. 1, illustrating a further embodiment.

Reference will first be made to FIG. 1 which shows a cylindrically tubular body 1 of rubber or other elastomeric material whose outer surface is formed with two annular peripheral grooves 10 at the ends and with a multiplicity of pits 11 accommodating tufts of bristles 12 between these grooves. A flexible but practically inelastic textile liner has been shown at 20.

Body 1 is mounted on a rigid support which comprises 15 a cylindrical sleeve 2 terminating at a shoulder 29 in a flared skirt with a frustoconical portion 30 and a cylindrical portion 31. A flange 17 of the latter portion bears upon an end face 19' of body 1 and forms one of two end members adapted to exert axial pressure upon that body, the other end member being a collar 3 which is screwed onto a male thread 15 of sleeve 2 and which has a flange 22 bearing upon the opposite face 19" of body 1. Lugs 16 and 18 on collar 3 and support portion 31 facilitate relative manual rotation thereof to change the 20 spacing between the two flanges 17 and 22, thus enabling the exertion of axial pressure upon the body 1 which thereupon bulges outwardly so that the tips of its bristles 12 lie on a generally-barrel-shaped surface 12'. This outward bulging of the body 1 allows the bristles 12 to yield inwardly, without breaking or buckling, whenever the brush encounters an obstruction within a pipe or other duct to be cleaned.

Sleeve 2 is rotatably mounted on a central rod 5 forming 25 an axial extension of a handle 9. Rod 5 terminates at one end in a set of peripheral ribs 24 by which it is anchored to a bell-shaped coupling member 4 having a cylindrical mouth 26 with a female thread 23 engageable with a complementary male thread on handle 9. The opposite end 25 of member 4, connected with its 30 mouth 26 through a tapered transition portion 28, bears through a washer 8 upon the shoulder 29 to form one end stop for the latter, another end stop being constituted by a cap nut 13 which engages a male thread 14 on the projecting free end of rod 5 and which is integral with an eye 6; the latter may be used to anchor the brush to a cable for pulling it through a pipe and, during periods of non-use, also serves for suspending the brush from a hook. A cotter pin, not shown, may be driven through holes 7 in sleeve 2 and aligned holes in cap 13 for preventing any unscrewing thereof.

In FIG. 2, in which elements already described are given the same reference numerals as in FIG. 1 but with the addition of a suffix *a*, sleeve 2*a* is formed on opposite extremities with respective male threads 15*a* and 24*a* engaged by relatively rotatable end members 3*a* and 38, these end members being provided with respective lugs 16*a* and 18*a* to facilitate their adjustment. A shoulder 33 adjacent thread 24*a* forms an end stop for member 38 which, in the assembly of the brush, is first screwed onto the sleeve 2*a* until it reaches its terminal position. Thereafter, member 3*a* is screwed onto thread 15*a* until the bristles 12*a* assume the desired barrel-shaped contour 12*a*'. A hollow coupling member 34 serves to lock the sleeve 2*a* against axial motion after being slid into an extremity of rod 5*a* to which it may be secured by a cotter pin passing through aligned holes 36 and 37; this member has male threads 35 by which it may be fastened to a handle that has not been shown but may be generally similar to handle 9.

In FIG. 3, where the suffix *b* has been used to designate elements already described and shown in preceding figures, rod 5*b* is integral with eye 6*b* and with a shoulder

14 forming one end stop for sleeve 2b; another end stop is constituted by a ring nut 59 which is screwed onto a thread 46 on the opposite end of rod 5b and has an inner flange 47 limiting its axial displacement toward shoulder 41. Bores 60 in the exposed surface of nut 59 facilitate its rotation by a suitable tool. Rod 5b is recessed between its enlarged ends 42 and 43 which alone serve for the rotatable support of sleeve 2b. The bulging shape of bristles 12b has been indicated at 12b'.

In FIG. 4, where elements previously identified have been given the same reference numerals with the suffix c, the support for tubular body 1c includes a cylinder 51 which underlies the major part of the inner periphery of tubular body 1c and has an end flange 55 bearing axially upon the latter. Cylinder 51 is threaded at 53 onto a disk 48 which, in turn, is screwed onto a thread 49 of sleeve 2c so as to come to rest against a shoulder 50 thereof. An inner flange 52 of cylinder 51 rides on the remote end of sleeve 2c and confronts a disk 56 which is screwed onto a male thread 57 of the sleeve and has a flange 58 forming the other pressure-exerting end member of the supporting structure for body 1c. In this embodiment, the presence of cylinder 51 positively prevents any inward deflection of body 1c whose outward curvature, paralleling the bulging contour 12c' of bristles 12c, has been indicated at 1c'. The assembly of this brush is analogous to that described in connection with FIG. 2.

I claim:

1. A pipe-cleaning brush comprising a cylindrical tubular body of elastomeric material; rigid cylindrical support means for said body and engaging the ends thereof; handle means connected with said support means; a pair of end members mounted on said support means and having freedom of relative axial adjustment for exerting axial pressure upon said body, thereby causing same to bulge outwardly; and a set of bristles extending generally radially outwardly from the periphery of said body.

2. A pipe-cleaning brush as defined in claim 1 wherein the ends of said body are provided along their outer surfaces with respective annular peripheral grooves overlying said support means.

3. A pipe-cleaning brush as defined in claim 2 wherein said body is externally formed with a multiplicity of pits between said grooves, said bristles being arranged in tufts respectively received in said pits.

5. A pipe-cleaning brush as defined in claim 1 wherein said support means includes a central sleeve, said handle means being provided with an extension rotatably surrounded by said sleeve.

10 6. A pipe-cleaning brush as defined in claim 4 wherein in said extension has a free end projecting beyond said sleeve abutment means on said free end for axially restraining said sleeve.

15 7. A pipe-cleaning brush as defined in claim 5, comprising an eye integral with said free end, said eye having a shoulder forming said abutment means.

8. A pipe-cleaning brush as defined in claim 1 wherein said abutment means includes a cap nut threadedly engaging said free end, further comprising an eye integral with said cap nut.

20 9. A pipe-cleaning brush as defined in claim 1 wherein said support means forms a throughgoing cylindrical surface underlying a major part of the inner periphery of said body.

25 10. A pipe-cleaning brush as defined in claim 1 wherein said body is provided with a flexible but substantially inelastic inner liner.
